PAPER PLACE MAT

William L. Davis, Prince Albert, Saskatchewan,
Canada

Application March 24, 1949, Serial No. 1,596

Term of patent 3½ years

(Cl. D59—2)

To all whom it may concern:

Be it known that I, William L. Davis, a subject of the King of Great Britain, residing in the city of Prince Albert, in the Province of Saskatchewan, in the Dominion of Canada, have invented a new, original, and ornamental Design for a Paper Place Mat, of which the following is a specification, reference being had to the accompanying drawing, forming part thereof.

The figure is a plan view, in reduced scale, of a paper place mat, showing my new design.

I claim:

The ornamental design for a paper place mat, as shown.
